CLAIM

The ornamental design for a thermal protector housing, as shown and described.

DESCRIPTION

FIG. 1 is a front elevational view of a thermal protector housing showing my new design;

FIG. 2 is a rear elevational view thereof;

FIG. 3 is a top plan view thereof;

FIG. 4 is a bottom plan view thereof;

FIG. 5 is a right side elevational view thereof, the left side elevational view thereof being a mirror image;

FIG. 6 is a front and upper right perspective view thereof;

FIG. 7 is a cross-sectional view thereof taken along line 7—7 of FIG. 6; and,

FIG. 8 is a rear and lower right perspective view of the thermal protector housing shown in FIGS. 1-7.

The broken line showing is included for the purpose of illustrating environmental elements only and forms no part of the claimed design.
